UNITED STATES PATENT OFFICE.

HENRY A. PISTORIUS, OF NEWBURYPORT, MASSACHUSETTS, ASSIGNOR OF
TWO-THIRDS TO CALEB STICKNEY AND GEORGE E. STICKNEY, OF SAME
PLACE.

DESIGN FOR A BREASTPIN.

SPECIFICATION forming part of Design No. 22,081, dated December 27, 1892.

Application filed November 12, 1892. Serial No. 451,823. Term of patent 3½ years.

To all whom it may concern:

Be it known that I, HENRY A. PISTORIUS, a citizen of the United States, residing in Newburyport, in the county of Essex and State of Massachusetts, have invented and produced a new and original Design for a Breastpin, of which the following is a specification, reference being made to the accompanying drawings, forming a part thereof.

Figure 1, shows a front view of my newly designed breast pin, and Fig. 2, the edge view thereof.

My design consists in the representation of two sea-shells *a*, *b*, one of which is lapped over

upon the other, and upon the inner or concaved faces of said shells, pins are represented one of which is of ancient type, as *c*, and the other of which is of modern type, as *d*.

I claim.

The design for a breastpin, substantially as herein described.

In testimony whereof I have signed my name to this specification in the presence of two subscribing witnesses.

HENRY A. PISTORIUS.

Witnesses:

J. T. BROWN,
JOHN L. KNIGHT.
